INVENTOR:

Claudius Dornier.

UNITED STATES PATENT OFFICE.

CLAUDIUS DORNIER, OF FRIEDRICHSHAFEN, GERMANY, ASSIGNOR TO THE FIRM
LUFTSCHIFFBAU ZEPPELIN GESELLSCHAFT MIT BESCHRANKTER HAFTUNG,
OF FRIEDRICHSHAFEN, GERMANY.

HYDROAEROPLANE.

Application filed June 28, 1920. Serial No. 392,555.

To all whom it may concern:

Be it known that I, CLAUDIUS DORNIER, a citizen of the German Empire, residing at Friedrichshafen, Germany, have invented 5 certain new and useful Improvements in Hydroaeroplanes (for which I have filed application in Germany February 5, 1915), of which the following is a specification.

The dropping of explosives in the case of 10 hydroaeroplanes is achieved in the most simple manner through an opening in the floor of the boat or the floats, over which the explosives are suspended ready for dropping. By this means the suspension of bombs out 15 side the boat connected with manifold inconveniences is avoided. A disadvantage of this arrangement consists in the risk of precipitation for the person suspending and dropping the bombs as well as in the fact 20 that the openings must temporarily, more especially whilst floating on the water, be kept closed. These faults are remedied in accordance with the present invention by surrounding the opening in the floor in the 25 interior of the boat with a hollow vertical shaft forming an open top compartment with a free passage to the exterior of the bottom which extends accordingly to the opening well nigh across the total beam of 30 the boat and to a corresponding length, and can, for the rest, have a cross-section according to choice. All risk of precipitation being prevented by the walls of the shaft forming a kind of parapet, several large- 35 sized bombs as well as observatory instruments such as sighting telescopes, photographic apparatus, etc., can be suspended without delay at the suitable moment. On account of the occasional floating on the 40 water, the height of the shaft, it is true, must not be less than a certain minimum as the fluid in the course of floating shoots upwards through the aperture provided in the gliding-floor of the boat, if the large 45 opening is not kept closed by a complicated device, whilst moving on the water.

By the installation of the shaft carried up to an adequate height the serviceableness

and permanent readiness for use of the flying-boat is materially increased, as the 50 bombs and equipments are continually safeguarded from the influences of the wind and the water during the flight in the air and the motion on the water, yet remaining in constant readiness for use without there being 55 any need to temporarily close up the lower opening of the shaft. The drawback, which is still attached to a high wall of the shaft on account of the additional weight and the decrease in space, can also be remedied. 60

This inconvenience is removed in accordance with the present invention by arranging the shaft in such a place on the boat that its lower aperture appears right behind a step in the floor of the boat. Experiments 65 have proved that in this case even with low and medium speeds of running no water rises through the opening. With higher speeds the boat rises to the step and now the 70 floor is even dry on the level of the dropping aperture, i. e. it is no longer washed by the water. In such an arrangement of the box-shaped shaft, even if it almost occupies the full beam of the boat, there is moreover the possibility of making the walls of 75 the shaft riddled or railed and thus attain a further considerable reduction in weight.

The position of the dropping aperture right behind the step offers still another advantage. For the air through it has access 80 in the most ample manner on account of the breadth of the shaft-opening to the step and to the part of the floor situated behind the step. As is well known, starting is materially facilitated by this means, for the 85 backward portion of the floor of the boat which remains more or less dry, then only calls forth a very small running resistance.

In the drawing attached to this specification and forming part thereof, two modifications embodying my invention are illustrated.

Fig. 1 is a vertical longitudinal section, and Fig. 2 is a plan of a boat having a rectangular opening or passageway, while 90

Figs. 3 and 4, respectively, are similar 95

views of a boat having an opening or passageway of triangular section.

Throughout the figures 1 is the hull, 2 is the bottom step, 3 is the bottom opening, 4 and 5, respectively, are the internal compartments, and 6 and 7, respectively, the walls surrounding them.

I claim:

A flying boat comprising a hydroplaning hull provided with a bottom step, a bottom

opening, and an internal compartment, the walls of which surround the opening and extend vertically upward, the opening forming a passageway from the compartment through the bottom and through which articles may be dropped, the forward boundary of the opening being located at the step. 15

In testimony whereof I affix my signature.

CLAUDIUS DORNIER.
